UNITED STATES PATENT OFFICE.

FRANK H. McFARLAND, OF FORT WORTH, TEXAS.

SCREEN-DOOR HINGE.

1,053,421.

Specification of Letters Patent.

Patented Feb. 18, 1913.

Application filed February 7, 1912. Serial No. 676,018.

To all whom it may concern:

Be it known that I, FRANK H. McFARLAND, a citizen of the United States, residing at Fort Worth, in the county of Tarrant and State of Texas, have invented certain new and useful Improvements in Screen-Door Hinges, of which the following is a specification.

This invention relates to hangers for screens, and the object is to provide simple and inexpensive hangers which can be used for hanging full length screens and also for hanging half length screens and which will be strong and durable and which will not be displaced in usage.

Another object is to provide hangers which will not only serve efficiently for hanging the screens, but will also serve as stays or braces for the screen frames, as will appear from the accompanying description and drawings.

Other objects and advantages will be fully explained in the following description and the invention will be more particularly pointed out in the claim.

Reference is had to the accompanying drawings which form a part of this application.

Figure 1 is a front elevation of a portion of a window frame, showing the manner of using the hangers on a full length screen. Fig. 2 is a front elevation of a portion of a window frame and a portion of a screen frame, showing the manner of hanging a half length screen. Fig. 3 is a side elevation of a hanger and the hook which the hanger engages. Figs. 4 and 5 show variations in the ends of the wire which form the hanger.

Similar characters of reference are used to indicate the same parts throughout the several views.

Each hanger consists of a length of wire bent upon itself and twisted a portion of the length of the doubled portion. An eye 1 is formed at the end of the doubled portion to engage a hanging hook 2. Another eye or opening is formed at 3 to receive a securing screw 4. The hangers are rights and lefts on a half length screen and when used on full length screens the hangers may be said to be lefts and rights because the hanger used on the right side of a half length screen can be used on a full length screen by transferring it to the left side and

turning the same one quarter turn, and the hanger used on the left side of a half length screen can be used on a full length screen by transferring it to the right side and turning the same one quarter turn. One 60 arm 5 is extended in line with the body of the twisted portion and the other arm 6 is bent at right angles to the body of the twisted portion. The arm 5 is bent at right angles to form a stay 7 to be driven into the 65 screen frame, and the arm 6 is also bent at right angles to form a stay 8 to be driven into the screen frame.

In Fig. 1 the stay 8 is driven into the frame piece 9 and the stay 7 is driven into frame piece 10. In Fig. 2 the stay 8 is driven into the frame piece 11 and the stay 7 is driven into the frame piece 9. In a similar manner the arms 12 and 13 are provided with stays to be driven into the frame 75 pieces of the screen. In Fig. 1 the arm 12 engages the frame piece 9 and the arm 13 engages the frame piece 11.

In Fig. 2 the arm 12 engages the frame piece 10 and the arm 13 engages the frame 80 piece 9. The hooks 2 may be provided with threaded shanks 14 to be screwed into the window facings. It will be noted that one arm of each hanger engages one frame piece and that the other arm engages the adjoining 85 frame piece of the screen frame. The frame pieces are thus securely braced after the hangers are secured to the frame pieces. After the stays are driven or inserted into the frame pieces, the screws 3 are inserted 90 to bind the hangers securely to the screen frames. The hangers engage the hooks 2 loosely.

The twisting of the wire makes a strong 95 brace for holding the frame pieces of the screen rigidly together in their normal positions.

The variation shown in Fig. 5 consists in forming eyes 15 for screws to take the place of stays 7 and 8. The variation in Fig. 5 100 consists in making a short bend in the wire before forming the stay. This construction would form a head for the stay.

Having fully described my invention, 105 what I claim, is,—

Interchangeable hangers for half and full length screens, the hanger for each upper corner of a screen consisting of a hook to be secured to the window facing, a length 110 of wire bent upon itself and twisted and

forming one eye at the bend thereof to engage said hook and another eye between the members of the twisted portion for a securing screw and one arm of the wire having 5 a stay formed thereon to engage one frame piece of the screen and the other arm of the wire having a stay formed thereon to engage the adjoining frame piece of the screen, and a securing screw coöperating

with said stays to bind the hanger to the 10 screen frame.

In testimony whereof, I set my hand in the presence of two witnesses, this 17th day of January, 1912.

FRANK H. McFARLAND.
